AUSTRALIA.

BLOTTING ATTACHMENT FOR FOUNTAIN-PENS.

1,248,304.

Specification of Letters Patent. Patented Nov. 27, 1917.

Application filed November 21, 1916. Serial No. 132,515.

To all whom it may concern:

Be it known that I, ADA CAROLINE FURLONGER, a subject of the King of Great Britain, residing at No. 78 Quarry street, 5 Ultimo, near Sydney, in the State of New South Wales and Commonwealth of Australia, have invented a new and useful Improved Blotting Attachment for Fountain-Pens, of which the following is a specification.

This invention relates to an improved blotting attachment for fountain pens and like writing appliances and has been specially devised to provide readily available 15 in conjunction with said pen and appliances means for blotting writing and so rendering such pen more particularly suitable than heretofore for travelers, collectors, canvassers and others and for outdoor use generally. 20 This improved blotting attachment for fountain pens comprises a spring hinged pair of leaves adapted to be held when folded or closed together by a convenient catch or fastening and when opened against a 25 stop or stops to present a flat surface amenable to pressure. On the hinge pin of the pair of hinged leaves is affixed a pivoted spring or other clip or grip whereby the attachment is removably attached and held 30 upon the stem of a fountain pen or other writing appliance as desired, or a gripping cap or clamp to receive the pen end may be suitably hinged to one of the leaves in any 35 convenient manner. Each leaf has suitable and convenient devices thereon or therein for removably affixing blotting paper or other like blotting material thereto.

But in order that this invention may be easily carried into effect an embodiment 40 thereof will now be described with reference to the drawings wherein Figures 1 and 2 are perspective views of same shut and open respectively and Figs. 3 and 4 corresponding cross sectional elevations while 45 Fig. 5 is an enlarged view of the hinge and Fig. 6 a section of same on plane 6—6 of Fig. 5.

The bracket or jaw 8 of the spring clip 50 7 is riveted at 9 to the hinge pin or arbor 10 or may be integral therewith on which arbor the knuckles or bosses 11 of one leaf 15 and similar knuckles 12 of the other leaf 16 are threaded. Helical springs 13 and 14 are anchored to said arbor 10 and have thrust 55 or free ends 17 and 18 respectively taking

above leaves 15 and 16. Stops or thrust lugs 19 and 20 are affixed to knuckles 11 and 12 to stop the respective leaves (preferably bedding in recesses). The leaves each have turn-overs or clipping edges 21 (preferably 60 also turned back) and one has a hinged clip or keeper 22 on one edge.

The leaves are loaded with blotting paper or the like 23 by insertion of same under the clipping edges 21 and they might cross over 65 the two leaves and the "blotter" device is affixed on a pen say a fountain pen by inserting the stem of such pen in the spring clip 7 as indicated by dotted lines in Fig. 1. For carriage and when out of use the clip 70 22 on leaf 16 is placed over the edge of the closed-in leaf 15 and holds the blotter inoperative and the closed leaves may be positioned as in Fig. 3. For use on the clip 22 being released the leaves or pads immediately open out wide by the action of springs 75 13 and 14 and rest against the stops or lugs 19 and 20 respectively and the blotting paper or the like 23 is exposed for use and may be applied to wet writing by means of the stem 80 of the pen in clip 7.

What I claim as my invention, and desire to secure by Letters Patent is:—

1. A blotting attachment for a fountain pen or like appliance comprising a clip, a 85 bracket attached to said clip, an arbor pivoted to said bracket, leaves having knuckles engaging said arbor, a spring on said arbor having thrust ends engaging said leaves, stops limiting the movement of said leaves, 90 clipping edges on said leaves for securing blotting material, and a keeper for holding said leaves together, substantially as described.

2. In an attachment for fountain pens 95 and the like, a clip adapted to be removably secured to the fountain pen body and a blotter carried by said clip comprising a pair of pivoted leaves carrying blotting material, a spring for opening said leaves to present a 100 flat blotting surface, and a keeper for fastening said leaves together.

In testimony whereof I have signed my name to this specification in the presence of two subscribing witnesses.

ADA CAROLINE FURLONGER.
